UNITED STATES PATENT OFFICE.

BENJAMIN BURTON LACY, OF HOUSTON, TEXAS, ASSIGNOR TO HENRY E. ELROD COMPANY, A COPARTNERSHIP CONSISTING OF HENRY E. ELROD, OF DALLAS, TEXAS, AND BENJAMIN B. LACY, OF HOUSTON, TEXAS.

POWER-GENERATING UNIT FOR LOCOMOTIVE-HEADLIGHTS.

1,357,501.

Specification of Letters Patent.

Patented Nov. 2, 1920.

Application filed August 15, 1917, Serial No. 186,408. Renewed September 24, 1920. Serial No. 412,621.

To all whom it may concern:

Be it known that I, BENJAMIN B. LACY, a citizen of the United States, residing at Houston, in the county of Harris and State 5 of Texas, have invented certain new and useful Improvements in Power-Generating Units for Locomotive-Headlights, of which the following is a specification.

This invention relates to power generating units for locomotive headlights, and particularly, to the turbine element of the 10 unit.

One of the objects of the invention is to provide a cheap, durable and efficient unit 15 for headlights, consisting of a turbine and a generator which may be contained within a relatively small space.

Another object of the invention is to provide means whereby the steam consumption 20 will be regulated by a novel speed responsive device in proportion to the load.

It is also the purpose of the invention to contain both the rotor of the turbine and the generator within a single case, but in 25 such manner, that the generator will be protected against deterioration by the steam from the turbine.

Other objects and advantages will be especially referred to hereinafter, it being understood that changes in form, proportion, and minor details of construction, will be resorted to without departing from the spirit of the invention, or sacrificing any 30 of its advantages.

35 In the drawings:—

Figure 1 is a longitudinal sectional view through the turbine.

Fig. 2 is a cross-sectional view through the turbine casing.

40 Fig. 3 is a detail view showing the governor weights and the actuating collar.

Referring now to the drawings by numerals of reference, 10 designates the casing for the unit, with two portions 11 and 13, the one designated 11 being removable. The end 13 of the casing is provided with a packing gland 14 for the shaft 15. One 45 end of the shaft 15 carries the rotor of the turbine and the other end the generator,

the generator being of any preferred construction. The shaft 15, of course, is journaled in suitable end bearings. The turbine casing is provided with an inlet 21 normally open by a balanced valve 22 on a stem 23, carrying a head or flange 24, between which and the abutment 25, is an expansion spring 26, said spring being normally opposed by a governor element as will appear hereinafter.

The shaft 15 carries an impulse wheel 27 on the periphery of which is a single row of impulse blades 28 registering with the nozzle 29 which communicates with the inlet 21. As the nozzle is within the inner circumference of the row of blades, a radial flow turbine is provided, so that steam may pass from the nozzle 29 through the blades out into the chamber 30, and pass the space 31 to the exhaust 32. Within the chamber 30 is a longitudinally movable collar 33 sleeved on the shaft 15 and having its longitudinal movement normally opposed by a spring 34 sleeved on the shaft 15, said spring 34 having one end seated against a movable abutment 35 and the other against a tensioning seat 36, said seat being moved with respect to the shaft through the medium of an adjusting screw 37 threaded in the disk 27 with one end bearing against the member 36. The collar 33 is provided with a circumferential flange 38 which is connected to the abutment 35 by the rods 39 and 40, said rods being spaced apart as best shown in Fig. 2. Inasmuch as the sleeve 33 is tied to the movable abutment 35, and inasmuch as the spring 34 is an expansion spring, it follows that the normal tendency of the sleeve or collar 33 will be to rest against the impulse wheel 27, the force necessary to oppose this tendency being determined by the adjustment of the tensioning device 36. Adjacent to the periphery of the flange 38 and on opposite sides of the axial center of the shaft 15 are weighted elbow levers or speed responsive devices 41 and 42. Each elbow lever has a flange engaging end 43, the opposite horizontal end being provided with a weight. As the wheel

27 rotates, it carries with it the collar 33, the rods 39 and 40, the tensioning device 36, the movable abutment 35 and the elbow levers 41 and 42.

5 The outer end of the collar 33 bears against the disk 44 received in a head 45 to which is swingingly secured the forked end 46 of a lever 47 pivoted to the bracket 48 carried by the head 11. The free end 10 of the lever 48 is provided with a threaded barrel 49 in which is an adjusting screw 50 adapted to be held in its adjusted position by a winged lock nut 51, the free end 15 of the adjusting screw being also adapted to bear against the head 24 of the valve stem 28. When the wheel 27 is rotating, the centrifugal force will cause the weighted ends of the levers 41 and 42 to move toward the periphery of the wheel, and as a 20 result, the pressure exerted by the ends 43 of said levers will impart a longitudinal movement to the collar 33 in opposition to the expansion spring 34. The greater the speed of the wheel, the greater the movement of the collar 33, and consequently, the closing movement of the valve 22. When the speed of the wheel diminishes, the spring 34 will move the collar toward the wheel 27 so that the spring 26 may permit the valve 30 22 to move to open position.

When it is desired to adjust screw 50, it will only be necessary to remove the screw plug 52 in the end 11, because the plug 52 is in alignment with the screw 50. Therefore, it will be seen that the valve may be adjusted without removing the end 11 or disturbing any of the bearings, etc. When it is desired to have access to the interior of the turbine end of the casing, it will be 40 only necessary to remove the fastening devices for the end 11, whereupon the entire end 11 may be taken off without disturbing any of the interior mechanism of the turbine.

45 I have not described the particular form of generator, inasmuch as any form of generator may be employed in connection with the turbine herein described.

It will be apparent that a device constructed in accordance with the one herein described, may be easily assembled and be rugged in operation and the parts may be readily accessible for inspection or repair.

I claim:—

55 1. In a machine of the character described, a casing, an impulse wheel mounted in said casing, a tensioning device on one side of the wheel and a slidible governing element actuated by said tensioning device on the other 60 side of the wheel, an inlet opening, a valve for controlling the effective port area of said opening, and a governor lever for controlling said valve, having one end connected with said slidible governing element; whereby the centrifugal force gener-

ated by the wheel may impart movement to said lever and actuate said valve.

2. In a machine of the character described, a casing having a removable cover part, an impulse wheel rotatable within 70 said casing, a valve for controlling said wheel and a governor for said valve, comprising a lever, said lever pivoted to and carried by the removable cover part of said casing, and having one end terminating in 75 actuating relation to said valve and its other end associated with means responsive to the centrifugal force generated by the wheel for imparting movement to said valve.

3. In a device of the class described, a 80 casing having an inlet, an outlet and a removable cover part, an impulse wheel within 85 the casing, a valve for controlling the effective port area of the inlet opening, a lever pivoted to and carried by said cover part, means at one end of the lever for contact with the valve, a longitudinally slidible element for engagement with the other end of the lever, speed responsive weights for actuating said element, a spring-actuated 90 tensioning device on the other side of said wheel, and means connecting said element and said tensioning device.

4. In a device of the class described, a 95 casing having an inlet, an outlet and a removable cover part, an impulse wheel within 100 the casing, a valve for controlling the effective port area of the inlet opening, a lever pivoted to and carried by said cover part, means at one end of the lever for contact with the valve, a longitudinally slidible element for engagement with the other end of the lever, speed responsive weights for actuating said element, a spring-actuated 105 tensioning device on the other side of said wheel, means extending through said wheel and terminally connected to said element and said tensioning device, respectively, and means carried by the wheel for adjusting 110 said tensioning device.

5. In a device of the class described, a 115 casing having an inlet, an outlet and a removable cover part, a shaft in said casing, an impulse wheel on said shaft, a flanged collar slidable on said shaft; weighted elbow levers carried by said wheel and adapted to impart longitudinal movement to said collar, a valve-actuating lever pivoted to and carried by the removable cover part of the casing, and having one end provided 120 with an adjustable contact with the valve for the inlet opening, means on the other end of said lever for engagement with the collar, an adjustable spring seated on the opposite side of said wheel, an abutment 125 spaced therefrom, a spring interposed between the seat and the abutment, and rods connecting the abutment with the collar.

6. In a device of the class described, a 130 stator and a rotor, a valve for governing the

effective inlet port area of the stator, a spring for maintaining the valve in unseated position, a lever for contact with said valve to oppose said spring, one end of said lever having a bifurcated portion, means on one side of the rotor for imparting movement to the end of said lever, and a spring-pressed de-

vice on the other side of said rotor to oppose the sliding movement of said means.

The foregoing specification signed at 10 Houston, Texas, this 2nd day of March, 1917.

BENJAMIN BURTON LACY.
